NONRETURN DEVICE

Philip George Marr, Walton-on-Thames,
EnglandApplication November 27, 1931, Serial No. 577,680
In Great Britain January 5, 1931

10 Claims. (Cl. 206—56)

This invention relates to a non-return device of the type comprising a barrel that is open at one or both ends and contains a non-return plunger of the kind having one or more parts, such as 5 teeth, for engaging with the internal periphery of the barrel and preventing movement of the plunger in the barrel in one direction, but not in the other. When the barrel constitutes the body portion of a case or container it is adapted to 0 hold an article, for instance a stick of shaving soap or the like resting on or against the plunger. Thus if the case or container is used for receiving a shaving stick, as the top end of the shaving stick becomes worn down by ordinary use, the 5 plunger may be pushed forward from the rear to expose a fresh length of shaving stick above the top rim of the barrel.

This invention has for one of its objects to provide an improved construction of device of 20 the type referred to wherein the plunger is prevented from overturning or rocking out of its normal position even when severe pressure is applied to it either forwardly or rearwardly at one point on its periphery. Another object is to provide an improved construction of plunger which 25 can serve as a seal for containers and sliding bolts.

According to the invention, there is provided a non-return plunger comprising a front transverse end wall, a rearwardly-extending peripheral wall 30 constituting a skirt carried thereby, a transverse leaf spring that is unattached to said end wall and has one or both of its ends extending through an aperture or apertures in the skirt, and means supporting said spring near its ends so as to cause 35 it to be flexed rearwardly while permitting it freedom of bending movement along its entire length. As compared with non-return plungers of constructions known heretofore, the improved 40 plunger according to the invention results in increased efficiency in upward movement, resistance to reverse pressure, and non-tilting combined with compactness, and is also suitable for use in tubes composed of various materials and having a smooth bore. Also, a wide range of 45 choice of materials is available for the body of the plunger. Moreover, the improved construction, besides providing for anti-tilting has the great advantage of compactness, the spring lying mainly within the body of the plunger. Further, 50 owing to the "floating" arrangement of the spring, the plunger can be fed forwards very smoothly and evenly, without jerks, which is important when it is desired to eject quite small quantities of material, e. g. paste or cosmetics, from a container equipped with the plunger.

According to a feature of the invention, the leaf spring in the plunger, may be supported in a rearwardly flexed condition by end portions of the spring bearing on marginal portions of the apertures. By altering the length of the spring at 30 the shoulders or by altering the position or depth of the slots receiving the ends of the spring, the middle of the spring can be caused to bear against or be spaced from the end wall of the plunger to any desired distance, thus providing various degrees of strength of running and resistance to reverse pressure.

The leaf spring composed of steel may have serrated ends, and the marginal portions of apertures in the skirt of the plunger for receiving the 70 serrated ends may have lugs, against which the ends of the spring bear.

Other features of the invention will be described hereinafter and pointed out in the claims.

Several embodiments of the invention are diagrammatically illustrated by way of example in the accompanying drawing wherein:

Figure 1 is a vertical section showing one form of barrel for use with a non-return device according to the invention,

Figure 2 is a perspective view showing one form of non-return plunger for insertion therein,

Figure 3 is a bottom plan view thereof,

Figure 4 is a perspective view of another form of plunger, Figure 5 is a bottom plan view thereof after the removal of an end cap, and Figure 6 is a perspective view of the said cap when removed.

Like reference characters designate like parts throughout the several views.

Referring to the drawing, the barrel 30 shown in Figure 1 is intended to receive a stick of shaving soap and carries a cover in the form of a slip-on cap 31, is open at the lower end 32 and at its upper end 33 and is adapted to receive in its lower end 32 any of the non-return plungers described hereinafter. Such a plunger, when inserted into the barrel, engages with the internal periphery of the barrel and can be moved upwards to propel a stick of shaving soap forward, but resists movement downwards.

Referring to Figures 2 and 3, a plunger 50 comprises an inverted sheet-metal cup-shaped body portion having a flat end wall 35 and an annular skirt 36 extending rearwardly from the latter. At opposite ends of a diameter the rear end of this skirt has formed in it two slots 51 extending along the skirt. Longitudinal marginal portions of each of these slots are turned to provide four inwardly-directed lugs 52. A leaf 110

spring 54, e. g. of steel, having sharp teeth 55 at both ends has portions of its ends cut away to provide shoulders 56 which, when the spring is bent and inserted into the cup as shown in Figure 2, lie above the upper ends of the lugs 52, whereby the spring is held in the body portion of the plunger in its position of use with the teeth 55 lying outside the skirt 36 at opposite sides thereof. The arch of the spring 54 may or may not bear against the inner face of the end wall 35. When it is suitably spaced slightly away therefrom, the advantage is obtained that when the plunger is inserted in the barrel and the inner wall of the barrel thereby presses the projecting ends of the spring inward, the space is taken up, and the middle of the spring comes into contact with the middle of the inner face of the end wall, without appreciably altering the angle at which the ends of the spring meet the inner wall of the barrel, and without causing the spring to be unduly compressed as might be the case if there were no such space, yet allowing the middle of the inner face of the end wall to act as a support when severe pressure is applied.

In this construction the endwise cuts forming the slots constitute slits which lie between the projections at the two ends of the spring and extend in the direction of length of the plunger. The plunger 60 shown in Figures 4, 5, and 6 comprises a slotted body portion 35, 36 similar to that described with reference to Figures 2 and 3, but differs therefrom in that no lugs 52 are provided at the sides of the slots 51. In this construction shoulders 56 formed at the ends of the spring 54 bear against the internal periphery of the skirt 36 at the ends 61 of the slots 51, and the spring 54 is retained in position in the body portion by a cap 62 shown in Figure 6. This cap has an annular peripheral wall 63 having at opposite ends of a diameter two slots 64 whereof the walls are recessed to provide a narrower end portion 65 in each slot. Between the two portions of each slot two shoulders 66 (which may be bent slightly inwards if desired) are thus formed which bear on the ends of the cross spring 54 at opposite sides thereof and retain the latter in position when the free edge 67 of the annular wall 63 bears against the inner face of the end wall 35 of the body portion of the plunger. In some cases the narrow portion 65 of the slot can be dispensed with. Also the cap 62 may be arranged to slide externally on the body portion of the plunger, instead of into the same. Also, in some cases, the cross spring 54 shown in Figures 2 and 3 and in Figures 4, 5, and 6 may extend through holes or perforations in the plunger, instead of through slots therein. When the plunger 60 is assembled the cap 62 may be secured in position on the body portion by dents or solder holding the two parts together.

When the plungers 50 and 60 are to be used in a barrel whereof the bore is not truly cylindrical but tapers slightly, the skirt 36 may have flexible lugs at opposite ends of a diameter that lies at right angles to the cross-spring 54 for preventing rocking of the plunger in the wider end of the barrel.

Various constructions of barrel may be employed. When it has a smooth bore, as shown in Figure 1, it may be composed of a material, for example metal (such as brass or aluminium) celluloid, papier-mâché, phenolic condensation product, waxed cardboard or the like, softer than the material, for example steel, of which the projections aforesaid, such as teeth 55, are composed,

The invention is also applicable to cases or holders for sticks of shaving soap and the like of the type usually known as "holder-top" cases or holders comprising two parts, whereof one is a so-called "holder-top" having a tubular portion for carrying the contents of the case, and the second is a cover detachably carried thereby.

The invention may be applied to sealing a tubular outlet of a container against its being opened by an unauthorized person. For example, the tubular outlet closed by a cork may have a corrugated or grooved end portion into the upper end of which can be inserted a non-return plunger 60, as illustrated in Figure 4, having its end face 35 downwards.

Also, the invention may be applied to sealing a sliding bolt. For example, when a barrel open at both ends serves to receive a sliding bolt carrying a handle member for moving it into and out of a keeper, a plunger such as 60, may be inserted (after the bolt has been shot home) into that end of the barrel which is remote from the keeper and which is preferably grooved internally.

In all of the described constructions, the body of the plunger cannot rock or overturn when pressure is applied to it in either direction, even if such pressure be applied near the periphery of the plunger, so that the plunger will make substantially anti-tilting fit with a barrel containing it.

Although a multiplicity of teeth is shown in the plungers illustrated in Figures 2, 3 and 4, the number thereof may be reduced to as few as one, in some cases. Also, in some cases, the ends of the cross spring 54 need not be serrated.

Various modifications may be made in the details of construction described above without departing from the invention. For example, in some cases the end face 35 of a plunger may have parts thereof removed in order to increase the flexibility of the skirt.

Also, the end wall 35 may carry means for receiving the (e. g. screw-threaded) end of a shaving stick or an attachment carried by the latter. Moreover, the skirt 36 of a plunger may be split in the direction of its length for providing increased resilience.

I claim:

1. A non-return plunger comprising a front transverse end wall, a rearwardly-extending peripheral wall constituting a skirt carried thereby, a transverse leaf spring that is unattached to said end wall and has its ends extending through apertures in the skirt at opposite sides thereof, and means supporting said spring near its ends so as to cause it to be flexed rearwardly while permitting it freedom of bending movement along its entire length.

2. A non-return plunger comprising a front transverse end wall, a peripheral skirt extending rearwardly therefrom and having two apertures at opposite ends of a diameter thereof, a leaf spring having its ends extending through said apertures, which spring is free from said end wall and is supported in rearwardly flexed condition by end portions bearing on marginal portions of the apertures.

3. A non-return plunger comprising a front transverse end wall, a peripheral skirt extending rearwardly therefrom and having two apertures at opposite ends of a diameter thereof, and a steel leaf spring having serrated ends extending through said apertures, which spring is free from said end wall and is supported in rearwardly

flexed condition by shouldered end portions bearing on marginal portions of the apertures.

4. A non-return plunger comprising a front transverse end wall, a peripheral skirt extending rearwardly therefrom and having two apertures at opposite ends of a diameter thereof, marginal portions of which apertures are inturned to form lugs, a leaf spring that is free from the said end wall and extends through said apertures, the ends of which spring are cut away to form shoulders arranged to bear against said lugs, and hold the spring in a rearwardly flexed condition.

5. A non-return plunger comprising a front transverse end wall, a peripheral skirt extending rearwardly therefrom and having two apertures at opposite ends of a diameter thereof, a leaf spring having its ends extending through said apertures, and a cap on the rear end of the skirt.

6. A non-return plunger comprising a front transverse end wall, a peripheral skirt extending rearwardly therefrom and having two apertures at opposite ends of a diameter thereof, a leaf spring having its ends extending through said aperture, and a cap that is carried by the skirt at its rear end and is arranged to engage the spring and retain it in position in the plunger.

7. A non-return plunger comprising a front transverse end wall, a peripheral skirt extending rearwardly therefrom and having two apertures at opposite ends of a diameter thereof, a cap carried by the skirt at its rear end and having at opposite ends of a diameter two apertures registering each with one of the apertures in the skirt, and a leaf spring extending through the apertures in the skirt and cap and retained in position in the plunger by the cap.

8. A non-return plunger having a body comprising a front transverse end wall, and a rear-

wardly-directed peripheral wall constituting a skirt that extends from the end wall and provides a cavity at the rear of the same, which body is so dimensioned as to external diameter and length as to make substantially anti-tilting fit with a barrel to contain it, and a transverse leaf spring that is unattached to said end wall and has at least one end extending through an aperture in the skirt at a situation spaced away from the end wall, and means supporting said spring near one end at an aperture so as to cause it to be flexed rearwardly while permitting it freedom of bending movement along its entire length.

9. A non-return plunger having a body comprising a front transverse end wall, and a rearwardly-directed peripheral wall constituting a skirt that extends from the end wall and provides a cavity at the rear of the same, which body is so dimensioned as to external diameter and length as to make substantially anti-tilting fit with a barrel to contain it, which skirt has an aperture in it at a situation spaced away from the end wall, and a leaf spring whereof one end portion extends through said aperture, and another portion of the spring bears against said end wall, which spring is supported in rearwardly-flexed condition by said end portion bearing on marginal portions of said aperture.

10. A non-return plunger comprising a front transverse end wall, a peripheral skirt extending rearwardly therefrom and having apertures at opposite sides thereof, and a rearwardly flexed leaf spring that is spaced away from said end wall extending through said apertures and supported near its ends so as to permit it freedom of bending movement along its entire length.
